UNITED STATES PATENT OFFICE.

HUGO GERNBSACK, OF NEW YORK, N. Y.

ELECTRIC VALVE

Application filed May 14, 1921. Serial No. 469,649.

To all whom it may concern:

Be it known that I, HUGO GERNBSACK, a citizen of the United States, residing at New York, in the county of New York and State 5 of New York, have invented certain new and useful Improvements in Electric Valves, of which the following is a specification.

This invention relates to improvements in electric valves commonly known as audions. 10 The objects of the invention are to increase the efficiency and sensitiveness of said valves, and to produce a more simple construction than heretofore employed.

I have found that a filament heated to red 15 or white incandescence in contact with the wall of a highly exhausted glass bulb produces a remarkably high current between the filament and an outside external electrode. The electronic flow is made to pass 20 between the filament and the outside element, although these two elements are not in metallic contact.

Under the heat of the filament, the wall of the glass vessel becomes a conductor which 25 allows the electronic charge to pass.

In the accompanying drawings, I have shown several illustrations of electric circuits in which the audion is mounted. In this showing:

30 Figure 1 is a diagrammatic view of the circuit of a wireless apparatus employing the invention,

Figure 2 is a slightly modified form, and,

Figure 3 is a view of one form of cooling 35 means employed in connection with the invention.

Referring to the drawings, the reference 40 numeral 1 designates the body portion of a the valve, which is preferably formed of a hollow glass tube in which a high degree of vacuum is maintained. A filament 2 is arranged within the bulb or globe contacting with the wall thereof at one point, as at 3. The two ends of the filament are passed 45 through the globe, as at 4, and connected to lead wires 5 and 6, leading to a source of current 7. A metal sleeve 8 is arranged around the clip adjacent the contact 3. This sleeve is in circuit with the coils 9 of a trans- 50 former 10, by means of a lead wire 11. A telephone receiver 12 may be arranged in the wire 11. The opposite end of the coil 9 is connected to the wire 5 by a connection 13, the wires 5 and 11 being provided with a 55 connection 14, passing through a variable condenser 15. The coil 10 is grounded, as

at 16, and is provided with an antenna 17, at its other end.

In the form of the invention shown in Figure 2 of the drawings, the filament 2 contacts with the globe in a similar manner and is connected to the source of current 7, as in the form shown in Figure 1 of the drawings. In this form of the invention, a pair of contacts 18 and 19 are arranged on the outside of the bulb, one of the contacts being connected to a source of current 20 by a lead wire 21. The opposite terminal of the source of current is provided with a lead wire 22, connected to the wire 5, and having a telephone receiver 23 arranged therein. In this form of the invention, the lead wire 11 which is connected to the coil 9 is provided with a condenser 24.

Due to the excessive heat developed at the point of contact between the filament and the glass vessel, it is necessary to provide some cooling means. Any suitable means may be employed for this purpose. In Figure 3 of the drawings, I have shown a pipe 25, arranged adjacent the globe 1 and adapted to spray water or other cooling fluid on the metal contact 8. Any suitable means may be employed for collecting the water, as illustrated at 26.

The filament when energized by the source of current 7 heats the globe 1 which is normally non-conductive, but it becomes conductive when heated to a fairly high temperature. When the glass wall of the vessel becomes conductive, current flows through the wire 11 from the source of current 7 in the form shown in Figure 1 of the drawings and from the source of current 20 in the form shown in Figure 2 of the drawings, to the wire 11, and thence to the coil 9. I have found that by means of the invention disclosed, a much more efficient valve is produced, due to its greater sensitiveness and its correspondingly increased efficiency.

It is to be understood that the forms of my invention herewith shown and described are to be taken as preferred examples of the same, and that various changes in the shape, size, and arrangement of parts may be resorted to without departing from the spirit of the invention, or the scope of the subjoined claims.

Having thus described my invention, I claim:

1. An electric valve comprising a bulb, a filament arranged therein and contacting

with the wall of the bulb, an electric conductor arranged in contact with the outer wall of the bulb, and means for energizing said filament.

5. An electric valve comprising a bulb, having a vacuum therein, a filament arranged in said bulb and contacting with the wall thereof at one point, an electric conductor arranged in contact with the outside 10 of the bulb, and means for energizing said filament.

3. An electric valve comprising a bulb, a filament arranged therein and contacting with the wall of the bulb, a metallic ring arranged on the outside of the bulb, said ring forming a conductor, and means for energizing said filament.

4. An electric valve comprising a bulb, a filament arranged therein and contacting

with the wall of the bulb, an electric conductor arranged in contact with the outside wall of the bulb, means for energizing said filament, and means for cooling said bulb.

5. An electric valve comprising a bulb, a filament arranged in said bulb and extending 25 substantially longitudinally thereof from end to end, the central portion of said filament being curved and contacting with the wall of the bulb, means for energizing said filament, and a metallic ring arranged 30 on the exterior of said bulb and forming a conductor.

In testimony whereof I affix my signature in presence of two witnesses.

HUGO GERNSBACK.
